US00D540292S

(12) **United States Design Patent** (10) **Patent No.:** **US D540,292 S**
Lee et al. (45) **Date of Patent:** **** Apr. 10, 2007**

(54) **PORTABLE PHONE**

(75) Inventors: **Ki-Eon Lee**, Seoul (KR); **Min-Hyouk Lee**, Gyeonggi-do (KR); **Nam-Mi Kim**, Seoul (KR); **Chang-Hwan Hwang**, Goyang-Si (KR)

(73) Assignee: **Samsung Electronics Co., Ltd.**, Suwon-si (KR)

(**) Term: **14 Years**

(21) Appl. No.: **29/232,777**

(22) Filed: **Jun. 24, 2005**

(30) **Foreign Application Priority Data**

Dec. 24, 2004 (KR) 30-2004-0039877

(51) **LOC (8) Cl.** **14-03**

(52) **U.S. Cl.** **D14/138**

(58) **Field of Classification Search** D14/191, D14/138, 147-148, 247-248, 144, 496, 156, D14/341-347; 379/433.01-433.13; 455/575.3, 455/566, 575.1, 556.1, 556.2, 90.3; D21/517; D16/208
